Des. 201,355
Patented June 15, 1965

201,355

EASY CHAIR

Pompeo Cavalli, 4 Via Don Minzoni, Bologna, Italy

Filed Mar. 21, 1962, Ser. No. 69,366

Claims priority, application Italy Sept. 23, 1961

Term of patent 7 years

(Cl. D15—1)

Fig.1

Fig. 2

Fig.3

FIG. 4

FIG. 5

FIG. 1 is a front elevational view of an easy chair showing my new design;

FIG. 2 is a side elevational view;

FIG. 3 is a top plan view;

FIG. 4 is a perspective view taken from the right front; and

FIG. 5 is a bottom plan view.

The back of the chair is plain and unornamented.

I claim:

The ornamental design for an easy chair, as shown and described.
